United States Patent Office.

JOSHUA ASHTON, OF RED WING, MINNESOTA.

Letters Patent No. 92,774, dated July 20, 1869.

IMPROVEMENT IN FANNING-MILLS.

The Schedule referred to in these Letters Patent and making part of the same.

To all whom it may concern:

Be it known that I, JOSHUA ASHTON, of Red Wing, in the county of Goodhue, and State of Minnesota, have invented a new and useful Improvement in Fanning-Mills; and I do hereby declare that the following is a full, clear, and exact description thereof, which will enable others skilled in the art to make and use the same, reference being had to the accompanying drawings, forming part of this specification.

This invention relates to improvements in fanning-mills, designed to improve the efficacy of the same, which improvements consist—

First, in an improved arrangement of the hopper, slide-gate, and shoe, for equalizing the grain upon the sieves;

Second, in an improved arrangement of spring-suspending devices for the shoe which support the sieves;

Third, in an improved arrangement of the orifices in the sieves for separating the grain;

Fourth, in an improved construction of the sieve-supporting shoe, whereby the pitch of the upper series can be adjusted without changing the others; and

Fifth, in an adjustable air-regulating slide for regulating the blast, and the delivery of the grain upon the final screen.

Figure 1 represents a side elevation of a fanning-mill, constructed according to my improvements, certain parts being broken out;

Figure 2 represents a partial section, showing the arrangement of the adjustable air-blast regulator;

Figure 3 represents a partial plan view of one of the sieves; and

Figure 4 represents a plan of one of the vanes of the fan.

Similar letters of reference indicate corresponding parts.

I construct the curb of the fan in two parts A B, separating them preferably on the horizontal line C, making the upper part B readily removable for access to the fan, for repairing or other purposes; and to secure the part B in place, I provide two buttons E upon the cross-beam of the frame at the top, for clamping it down.

I arrange the opening for the grain to pass from the hopper through the side G, as represented in dotted lines in fig. 2, discharging it in the direction opposite to that which it afterwards takes to pass to the sieves. I also extend the shoe H in this direction more than as now constructed, to cause the grain to pass over a board, I, for a considerable distance before arriving at the screen, to cause it to spread and be evenly distributed when it arrives at the sieves.

The hopper-slide G is arranged upon the part G of the hopper, for adjusting the opening for the grain.

I suspend the shoe H by the elastic metallic bands K, two on each side, arranged to cross each other, and riveted together at the place of crossing. This arrangement I find much more durable, and it main-

tains the shoe more exactly in the required position than any arrangement now in use.

As a better arrangement of the vanes of the fan to induce the air to flow in as much as possible, I taper the said vanes from the centre outwards, as represented in fig. 4, whereby the space is enlarged toward the opening, while the area of the fans is increased in the opposite direction, to take up the air and force it towards the sieves.

I propose to construct the sieves for separating the oats from the wheat of sheet-metal, preferably of zinc, and form the orifices, as represented at L, fig. 4, similar to the forms of the grains of wheat, but not long enough in any direction for the oats to pass through.

The sieve thus formed of sheet-metal presents a smooth surface, over which the oats slide freely without being thrown upon their ends, as in the case of the wire sieves, and thereby, when the orifices are constructed as shown, more effectually separate the two grains.

I propose to construct the sieve-shoe in two parts, and pivot the upper part at the rear to the posts O, common to both, suspending the front of the part N, by thumb-screw P, passing through the beam K, supported on the posts S, whereby the said part N may be raised or lowered at the outer end, to adjust the pitch of the sieves thereon without affecting that of the sieves in the lower part.

For governing the blast of air for action on the final sieve T, I provide the adjustable slide or deflector U, whereby, according to its position nearer to or further from the front of the shoe, the action of the blast may be caused to be more or less intense upon the final sieve, and the grain may be delivered nearer to or further from the front, which I find of great advantage in separating the lighter grains and other matter which fails to be separated before, the specific gravity of which changes materially in different qualities of grain.

Having thus described my invention,

I claim as new, and desire to secure by Letters Patent—

1. The arrangement of the opening and the adjusting-slide on the part G of the hopper, the shoe H, and distributing-board I, all substantially as specified.

2. The sieve-shoe suspended by the elastic metallic bands K, when arranged substantially as specified.

3. The improved sheet-metal sieves, provided with orifices L, formed substantially as specified.

4. The arrangement of the shoe in two parts, M and N, when the part N is hinged and suspended by thumb-screw P, substantially as specified.

5. The adjustable slide U, arranged between the final sieve and the upper sieves, substantially as and for the purpose specified.

Witnesses: JOSHUA ASHTON.

FRANK IVES,
DWIGHT M. BALDWIN.
